UNITED STATES PATENT OFFICE.

SIGMUND COHN, OF MILWAUKEE, WISCONSIN.

CIGAR-BOX.

SPECIFICATION forming part of Letters Patent No. 372,119, dated October 25, 1887.

Application filed March 15, 1887. Serial No. 230,950. (No model.)

To all whom it may concern:

Be it known that I, SIGMUND COHN, of Milwaukee, in the county of Milwaukee, and in the State of Wisconsin, have invented certain new and useful Improvements in Cigar-Boxes; and I do hereby declare that the following is a full, clear, and exact description thereof.

My invention relates to cigar-boxes, and will be fully described hereinafter.

10 In the drawings, Figure 1 is a longitudinal vertical section through an ordinary cigar-box provided with my improvements. Fig. 2 is a perspective view of a sample box, showing my improvement adapted thereto; and Fig. 3 is a perspective view of one form of my device.

Heretofore an objection has been found in the transportation of cigars in boxes when several cigars had been removed therefrom, in that those that remained, by rolling and bumping against each other in the moving of baggage containing the said boxes, were liable to become broken, torn, or injured, and thus render them unfit for smoking or for exhibition as samples, and the object of my present invention is to provide a remedy therefor. To this end I show both an ordinary cigar-box and a sample or tray box, as my improvement is adapted for both.

In Figure 1, A represents an ordinary cigar-box, the one shown being of the size to hold twenty-five cigars, or two layers; but the size of box or number of layers is immaterial.

35 In Fig. 2 I show a sample-box from which the tray has been removed, but which tray is designed to rest on the ledges *a*. In this latter form there would only be needed in the box proper one of my devices, as shown at B, consisting of a strip of any suitable material—such as tin, brass, or even heavy lead-foil—pressed into the 40 required number of corrugations, so that each corrugation shall snugly hold one cigar. This strip B has upwardly-bent ends *b b*, by means of which it is tacked or otherwise fastened to the ends of the box. In the form of box shown 45 in Fig. 2 the tray would be similarly fitted up. In a common cigar-box, such as represented in Fig. 1, this simplest form of strip B would be used on the bottom of the box only, while for the layers of cigars above the bottom layer 50 I would preferably use the form shown in Fig. 3, with the lateral extensions *C C* terminating in turned-up ends *c c* to be nailed against the

sides of the box, and then, as the cigars are held in place by the corrugations of the strips B, and held down by like strips above, there 55 can be no danger of the cigars rolling against each other, and thereby breaking the wrappers and becoming disfigured or broken.

The cover of the box will hold the top layer down in place in an ordinary box, and the bottom of the tray will serve the same purpose in the sample-box shown in Fig. 2; but the strips B can be made with corrugations deep and elastic enough to practically hold the cigars in place even when a layer above them 65 is removed, and thus by my invention a great objection to carrying cigars in boxes, whether for use in smoking or as samples, is obviated.

The strip B may be of any suitable material, and while thin sheet metal is probably the 70 best, I may employ any substance that can be bent, pressed, molded, or shaped into the desired form, such as wood, paper, fabric, leather, papier-maché, or any plastic composition.

As already stated, the number of layers of 75 cigars in a box is immaterial, and the number of my corrugated strips consequently would be the same, only one strip being employed for each layer. I have stated that the turned-up ends of these strips are tacked or otherwise fastened to the box ends. It is obvious, therefore, that for convenience, when, say, four of eight layers of cigars and a corresponding number of strips are placed in a box, it would be better to remove the top strip when there 85 are no longer any cigars immediately under it, (in the gradual emptying of the box;) but as there will be sufficient elasticity to the strips to enable them to be raised up enough to get a cigar out from under them, the removal of the strips is not necessary; only, as stated, it will be more convenient to have the upper strips out of the way when they are no longer useful.

Having thus fully described my invention, 95 which I claim as new, and desire to secure by Letters Patent, is—

1. The combination of a cigar-box with a series of narrow corrugated strips having turned-up ends, whereby they are removably 100 secured, one above the other, to the walls of the box at a distance apart just sufficient to receive a row of cigars between each two adjacent strips, substantially as set forth.

2. The combination of a cigar-box with a narrow elastic corrugated strip, B, having turned-up attaching ends b b, and central lateral extensions, C C, terminating in similar upturned attaching ends, c c, substantially as set forth.

In testimony that I claim the foregoing I

have hereunto set my hand, at Milwaukee, in the county of Milwaukee and State of Wisconsin, in the presence of two witnesses.

SIGMUND COHN.
